UNITED STATES PATENT OFFICE.

HENRY CASEBOLT, OF SAN FRANCISCO, CALIFORNIA.

GRIPE-OPERATING DEVICE FOR CABLE-WAYS.

SPECIFICATION forming part of Letters Patent No. 245,785, dated August 16, 1881.

Application filed March 17, 1881. (No model.)

To all whom it may concern:

Be it known that I, HENRY CASEBOLT, of San Francisco, in the State of California, have invented certain Improvements in Mechanism for Operating the Griping Device of Cars Propelled by Endless-Wire Ways; and I hereby declare the following to be a full, clear, and exact description thereof, reference being had to the accompanying drawings, making part of this specification, in which—

Figure 1 is a longitudinal sectional view through a car having the gripe-operating mechanism attached. Fig. 2 is a sectional view on the line xx of Fig. 1. Fig. 3 is a top view of the operating-lever. Fig. 4 is an enlarged view of the lower end of the supporting-pipe and contained rod.

Heretofore in endless-cable-way systems the cars have been successfully operated only by coupling them to a separate vehicle having little or no spring or yield, and known among cable-road operatives as a "dummy." This was necessitated because the gripe, if attached to the floor of a car resting on springs, was seriously affected by the vibration of the springs sustaining the loaded car. The comfort of the passengers rendered the springs necessary, and, as they could not be dispensed with, the gripe had to be attached to the dummy, as aforesaid, and to this dummy was coupled the car for containing the passengers.

The object of my invention is to avoid the necessity of using the dummy or separate truck for the gripe, and to attach the gripe-operating device directly to the passenger-carrying car; and my invention consists in mounting the gripe directly upon a frame-work attached to the car-axles and sustaining the fulcrum of the lever independently of the body of the car, whereby the vertical movement of the car-body due to the elasticity of the springs is not communicated to the gripe or cable.

In order that those skilled in the art may make and use my invention, I will proceed to describe the manner in which I have carried it out.

In the said drawings, A shows the section of a car the axles of which carry two longitudi-

nal angle-iron bars, C C, by means of boxes a a. These bars support the loose bars L 50 through the medium of staples b, which hold the gripping device, as fully described and claimed in the patent issued to me February 15, 1881, and No. 237,813. Four feet, h h, support above the gripe (shown in dotted lines) a 55 casting, H, having a central opening, into which is screwed a heavy pipe, F—say two inches in diameter—which passes through a box, E, in the bottom of the car and up through an opening, e, in the roof, and having screwed upon 60 the upper end a head, N, from which rise two parallel rack-bars, S S, (see Figs. 1 and 3,) between which lies a lever, D, having in its head a slot, t', in which bears an anti-friction roller, n, journaled on a stirrup at the upper end of 65 a rod, R, which passes down through pipe F, and is attached at its lower end to the moving jaw of the gripe. On each side of the center the segmental rack-bars have semicircular de- 70 pressions d d, to serve as bearings for the fulcrum of the lever, consisting of lugs d' on a line with the slot t'. The lever is provided with a double pawl, p, to engage the teeth of the rack-bar in whichever direction the lever is operated, the position of the man operating 75 it changing with the direction of the travel of the car. The length of pipe F is such that the extreme vertical movement of the car upon its springs will not in any manner affect it. A small circular fender, I, is attached to pipe F 80 above the roof, to prevent any rain or other objectionable matter from passing into the car through the opening surrounding the pipe.

It will be seen that I have provided a sup- 85 porting device for the gripe and a fulcrum or bearing through which to operate it, connected only with the axles of the car and entirely independent of the car-body and its supports upon the boxes, and consequently the vertical movement of the car is not transmitted to the 90 gripe or cable.

Rubber buffer-springs t are placed on rods connected with the gripe-supports L, so that when the gripe seizes the cable there will be an elastic resistance to overcome the inertia of 95 the car. The pipe is so much larger than rod

R that the rod can move with the vibration of the gripe on its supports L L. (See Fig. 4.)

Having thus described my invention, what I claim as new, and desire to secure by Letters 5 Patent, is—

1. In a car adapted to be propelled by an endless cable, the axles B B, in combination with and supporting a frame, C C, to sustain the gripping device, and an operating mechanism extending through the body of the car to its roof, substantially as described.

2. The pipe F, extending through the car, and the inclosed operating-rod R, in combination with head N, rack-bars S S, lever D, head H, provided with legs h h, bars C C, and axles 15 B B, all constructed, arranged, and operated substantially in the manner and for the purpose set forth.

HENRY CASEBOLT.
